BABBITTING MACHINE

Louis B. McBride, Flat River, Mo.

Application September 30, 1931
Serial No. 566,013

10 Claims. (Cl. 22—58)

My invention relates to a babbittting machine and particularly to one for applying semi-linings to connecting rods or similar bearing members. The object of my invention is to produce a machine for the purpose named which will be inexpensive in construction and simple in operation and which will insure the formation of a perfect lining.

In the accompanying drawings, which illustrate 10 a babbittting machine made in accordance with my invention, Figure 1 is a side elevation, the housing being shown in section; Figure 2 is a front elevation, the housing being shown in section; Figure 3 is an enlarged front view of the 15 upper part of the machine; Figure 4 is partly a top plan view and partly a section on the line 4—4 of Figure 1; Figure 5 is an enlarged section taken on the line 5—5 of Figure 4; Figure 6 is an enlarged elevation and plan of the core; Figure 7 20 is a bottom plan view and section of the upper semi-annular mould; Figure 8 is a top plan view and section of the lower semi-annular mould; and Figure 9 is a view similar to Figure 5 but showing a modified form of core.

25 Referring first to Figures 1 and 2, the base of the machine is formed of a housing 1 to which is pivoted at 2 a supporting plate 3 carrying a motor 4 and vibrator casing 5 within which is a cam 6 driven by the motor 4. The cam is adapted 30 to impart vibratory motion to a rod 7 which, however, is normally held out of contact with the cam by a spring 8. Positioned directly over the rod 7, and just out of contact therewith, is a rod 9 secured to the lower face of a plate 10 upon 35 which the babbittting mechanism is mounted. A bent lever 11 is pivoted to the housing at 12 and provided at one end with a treadle 13. The other end is connected by a link 14 to the plate 3 so that when the treadle is depressed the end of plate 3 40 is raised to cause the end of the rod 7 to contact with the rod 9, forcing the first named rod against the cam so that vibratory motion is imparted to the plate 10.

45 In order to allow the vibratory motion of the plate 10 it is yieldingly mounted on the housing by bolts 15, the downwardly projecting ends of which are surrounded by coil springs 16. Formed on the plate 10 is a support 17 for the mould which 50 comprises a core 18 and upper and lower semi-annular members 19 and 20, respectively. The core consists of a semi-cylindrical body and a flange 21, the body being provided with a threaded stud 22 by means of which the core is secured 55 in position. The flange preferably rests on a filler block 23 removably secured in position by a threaded stud 24. The member 19 has formed in its lower face, a groove 25 and the member 20 has formed in its upper face, a similar groove 26. 60 A pouring opening 27 is formed in the ring 19.

The connecting rod 28 to be babbitted, is positioned around the core and between the mould members 19 and 20, as shown in Figure 5, and the parts are held in position by clamping mechanism hereinafter to be described.

Carried adjacent to one side of plate 10 are a 65 post 30 and a post 31 forming guides for sliding bars 32 and 33. The bar 32 carries on its forward end a clamping flange 34 adapted to engage with the mould member 20, and the bar 33 carries at 70 its forward end a clamping finger 35 adapted to engage with the member 19. The latter finger is connected to the bar by a swivel joint 36 so as to compensate for variations in the thickness of the 75 bearings babbitted, and also to allow it to swing up into the position shown in Figure 4 to facilitate the assembly of the parts of the mould and the bearing to be lined. Bars 32 and 33 are moved longitudinally by a yoke 37 acting through coil springs 38. This cross bar is connected by a 80 link 39 with an operating lever 40.

Part 30 is provided with a lateral extension 41 (Figure 4) forming a guide for the rear ends of 85 sliding bars 42 provided at their forward ends with clamping fingers 43 for engagement with the connecting rod or other bearing to be lined. The forward end of the bars are guided in slots 44 in the support 17 so as to allow of adjustment of the distance between the fingers 43 to accommodate 90 bearings of different width. The bars 42 are moved longitudinally by a yoke 45 acting through coil springs 46. The connection of the bars with the yoke is made by slots 47 to permit of the movement of the bars toward and away from each other. The yoke 45 is connected by a 95 link 48 with an operating handle 49. Secured to the support 17 by bolts 50 is an upright 51. Rotatably mounted in the upright are a pair of internally threaded sleeves 52 provided with knurled heads 53 and engaging with threaded stems 54 and 55, respectively. Carried on the stem 54 is an upper guide bar 56 and on the stem 55 a lower guide bar 57. Sliding in these guide 100 bars are clamping bars 58, the ends of which are adapted to bear upon the upper face of the member 19. Slots are provided in the guide bar 57 to allow of the movement of the clamping bars toward and away from each other and this movement is regulated by set screws 59. A yoke 60, 105 acting through coil springs 61, moves the clamping bars 58. This yoke is provided with slots 62 (Figure 3) to permit of the lateral movement of the clamping bars, therefore, to prevent lateral movement of the yoke when it is actuated, I prefer to provide auxiliary bars 63 extending between 110 bars 56 and 57 to guide it. The yoke 60 is connected by a link 63 with an operating lever 65.

In Figure 9 I have shown a modification in which a core 18', not provided with a flange, is used instead of the flanged core previously de- 115 120

scribed. In this construction the filler block 23' is made thicker and the member 20 rests upon it instead of upon the core flange.

In using my machine the connecting rod or 5 other bearing is positioned around the core between the mould members 19 and 20, as shown in Figures 5 and 9, and the posts are clamped in position by operating the levers 40, 49 and 65. The molten babbitt is now poured into the bearing 10 through the pouring opening 27. During the pouring the treadle 13 is depressed to impart vibratory motion to the plate 10 and parts carried thereby to insure the complete filling of the mould.

15 Having fully described my invention, what I claim as new and desire to secure by Letters Patent of the United States is:

1. In a device of the class described, the combination with a support, of a core carried thereby, a pair of mould members adapted to be placed against said support one at each side of the bearing to be lined, clamping means engaging with the bearing lugs for holding the bearing against said support, clamping means arranged above and below said first named means and engaging the mould members for holding said mould members against said support, clamping means engaging the upper face of the top mould member and operating substantially at right angles to said 25 first named clamping means for holding the bearing and mould members together, and means for vibrating said support while the bearing is being lined.

2. In a device of the class described, the combination with a support, of a core carried thereby, a pair of mould members adapted to be placed against said support one at each side of the bearing to be lined, a pair of independently movable clamping fingers engaging with said bearing one 30 at each side of the core, common operating connections for both fingers, and equalizing means in said connections for compensating for inequality in the bearing engaged by the fingers.

3. In a device of the class described, the combination with a support, of a core carried thereby, a pair of mould members adapted to be placed against said support one at each side of the bearing to be lined, a pair of clamping bars provided with fingers engaging the bearing one at each 45 side of the core, a yoke having sliding engagement with said bars, a separate spring between each bar and the yoke, whereby compensating means for the fingers is provided, and an operating lever for actuating the yoke to cause the 50 fingers to clamp the bearing in position.

4. In a device of the class described, the combination with a support, of a core carried thereby, a pair of mould members adapted to be placed against said support one at each side of the bearing to be lined, a clamping means engaging with the bearing lugs for holding the bearing against said support, a pair of longitudinally movable clamping bars, fingers carried by said bars and adapted to engage with said mould members 60 above and below the bearing, one of said fingers being swiveled to swing upwardly and laterally away from the member with which it cooperates, and means for moving said bars longitudinally to engage said fingers with said mould members.

70 5. In a device of the class described, the combination with a support, of a core carried thereby, a pair of mould members adapted to be placed against said support one at each side of the bearing to be lined, clamping means engaging with

the bearing lugs for holding the bearing against said support, a pair of clamping bars, a pair of fingers carried by said bars for engaging with said mould members above and below the bearing, one of said fingers being swiveled to its bar, a yoke for actuating said bars, a spring interposed between each of said bars and the yoke, and an operating lever for said yoke, whereby the bars are simultaneously and differentially actuated.

80 6. In a device of the class described, the combination with a support, of a core carried thereby, a pair of mould members adapted to be placed against said support one at each side of the bearing to be lined, clamping means engaging with the bearing lugs for holding the bearing against said support, clamping means for holding said mould members against said support, a pair of clamping bars in addition to said clamping means and adapted to engage with the face of one of said mould members, and means for adjusting said bars toward and away from the support.

85 7. In a device of the class described, the combination with a support, of a core carried thereby, a pair of mould members adapted to be placed against said support one at each side of the bearing to be lined, clamping means for holding the bearing against said support, clamping means for holding said mould members against said support, a pair of clamping bars in addition to said clamping means and adapted to engage with the face of one of said mould members, means for adjusting said bars toward and away from said support, and means for adjusting the mould 90 engaging ends of said bars toward and away from each other.

95 8. In a device of the class described, the combination with a support, of a core carried thereby, a pair of mould members adapted to be placed against said support one at each side of the bearing to be lined, clamping means for holding the bearing against said support, clamping means for holding said mould members against said support, a pair of guide bars, clamping bars in addition to said clamping means and sliding 100 in said guide bars, one of said guide bars being provided with means for adjusting the clamping bars toward and away from each other, a yoke for said clamping bars, springs interposed between said yoke and bars, and an operating lever 105 for actuating said yoke.

110 9. In a device of the class described, the combination with a support, of a core carried thereby, means for securing a bearing against said support and around said core, a pair of mould members positioned one at each side of the bearing, a contact rod carried by said support approximately in line with the bearing axis, a reciprocating member, and means for moving said member toward and away from said rod to 115 variably vibrate the support.

115 10. In a device of the class described, the combination with a support, of a core carried thereby, means for securing a bearing against said support and around said core, a pair of mould members positioned one at each side of the bearing, a contact rod carried by said support approximately in line with the bearing axis; a vibrator including a rotating shaft, a cam, and a contact member driven from said cam; and means for 120 moving said vibrator toward and away from said rod to variably vibrate the support.
